UNITED STATES PATENT OFFICE.

ATHEAN C. ALLYN, OF BOSTON, MASSACHUSETTS.

STATION-INDICATOR.

SPECIFICATION forming part of Letters Patent No. 525,176, dated August 28, 1894.

Application filed October 30, 1893. Serial No. 489,612. (No model.)

To all whom it may concern:

Be it known that I, ATHEAN C. ALLYN, of Boston, in the county of Suffolk and State of Massachusetts, have invented certain new and useful Improvements in Station-Indicators, of which the following is a specification.

The object of the present invention is to provide means for positively engaging a roller or pulley and an apron, curtain or belt, where-
10 by a fixed relation is established. The ar-
rangement is designed for use in street and sta-
tion indicators which employ a curtain bear-
ing legends, and rollers one of which by its
rotation moves the curtain so as to display the
15 legends successively. In an appliance of this
character, it is of great importance that a
positive relation be established between the
driving-roller and the curtain, otherwise the
inscriptions on the latter will not be properly
20 displayed. While the invention is designed
to supply this desideratum in this class of de-
vices, yet it is not limited to such devices, and
may be employed in many other connections.

Of the accompanying drawings, which illus-
25 trate an embodiment of the invention: Fig-
ure 1 shows a front elevation of a street and
station indicator. Fig. 2 shows a side eleva-
tion of the parts which embody the invention.
Fig. 3 shows an end view of the same.
30 Fig. 4 shows a longitudinal section. Figs. 5
and 6 show detail views of a cam.

The same letters of reference indicate the
same parts in all the figures.

In the drawings: the letter *a* designates the
35 curtain of the indicator, which bears the leg-
ends, and *b* designates the driving-roller over
which said curtain passes.

In order to establish an unvarying relation
between the curtain and roller, it is necessary
40 to prevent any lost motion between them, and
to this end my invention provides means for
clamping the curtain to the roller as it is car-
ried around thereby. The means here shown
45 for accomplishing this design consists of a
series of nippers *c*, pivoted to support *c'*, on
a metallic sleeve *c''*, fastened on one end of
the roller *b*, said supports being within the
periphery of the sleeve, and the nippers be-
50 ing so formed that, when turned in one direc-
tion on their pivots, their engaging portions

are brought upon the curtain where it is in
contact with the roller; and, when turned in
the opposite direction, they are wholly out of
the path of the curtain. The nippers are nor-
55 mally thrown to this latter or outward posi-
tion by springs *d*, attached at one end to the
nippers on the inner side of their pivots, and
at the other end to the inner wall of the sleeve
c''. The outward position of a nipper is main-
60 tained until the rotation of the roller brings
it to that part of the curtain which lies flat
against the roller, and then the nipper is
brought over upon the curtain and clamps it
to the roller, and does not release its hold un-
65 til it arrives where the curtain leaves the
roller. The means employed for thus apply-
ing the nippers consists in a stationary cam
e, affixed to a suitable support by means of a
flange *e'*, and formed with a raised engaging
70 surface *e''*, of sufficient extent to be engaged
simultaneously by two of the nippers, which
are formed with outward-extending flanges *e'''*
to engage the cam. Under rotation of the
roller, when the nippers are at the low part
75 of the cam, the springs hold them in their out-
ward position, so that they do not interfere
with either stretch of the curtain, and when
the nippers arrive at the point where the cur-
tain engages the roller, they encounter the
80 high part of the cam and are applied thereby,
two nippers being at all times in action.

It will be seen that the above arrangement
establishes a positive engagement between the
curtain and roller.

The cam *e* tapers in thickness at each end
85 of the acting section, *e''*, and merges into a
partly circular V-shaped blade, *e'*, so that the
flanges, *e'''*, of the nippers will ride easily into
and off from said surface, *e''*, and will take over
and behind the blade *e'*, so as to be guided
90 thereby. Thus the nippers are at all times
properly controlled, being held to the cam and
blade by the springs, their outward movement
being limited by the blade.

Having thus described my invention, what
95 I claim as new, and desire to secure by Letters
Patent, is—

The combination with a roller and curtain
of nippers pivoted to the roller and adapted
to extend over the curtain and clamp the 100

same against the roller, said nippers having flanges projecting on the outer sides of their pivots, a fixed cam having a section which co-acts with the said flanges to move the nippers 5 against the roller and a tapered blade over which the flanges may take when the nippers move away from the roller, and springs impelling the nippers away from the rollers.

In testimony whereof I have signed my name to this specification, in the presence of 10 two subscribing witnesses, this 25th day of October, A. D. 1893.

ATHEAN C. ALLYN.
